UNITED STATES PATENT OFFICE.

MACIEJ SZYMKIEWICZ, OF JERSEY CITY, NEW JERSEY.

SAFETY-LOCK.

1,383,443.

Specification of Letters Patent. Patented July 5, 1921.

Application filed December 1, 1920. Serial No. 427,463.

To all whom it may concern:

Be it known that I, MACIEJ SZYMKIEWICZ, a citizen of the United States, residing at Jersey City, in the county of Hudson and State of New Jersey, have invented certain new and useful Improvements in Safety-Locks, of which the following is a specification.

The main object of this invention is to provide a safe lock which will not only make difficult the opening thereof but will also sound an alarm whenever the safe is opened, whether by one who is authorized to do so or whether by an unauthorized 15 person.

The above and other objects will become apparent in the description below, in which like characters of reference refer to like-named parts in the drawings.

Referring briefly to the drawings, Figure 1 is an enlarged view of the inner side of the safe door, showing the lock mechanism.

Fig. 2 is a side elevational view thereof.

Fig. 3 is a view similar to Fig. 1 with the 25 respective parts in another position.

Fig. 4 is a view taken on the line 4—4 of Fig. 3.

Fig. 5 is a perspective view of one of the wheels of said mechanism.

Fig. 6 is an enlarged perspective view of one of the safety features of said mechanism.

Fig. 7 is an enlarged side elevational view of the door shown in Fig. 1 with the respective parts in another position.

Fig. 8 is a view of the inner side of the inner safe door.

Fig. 9 is a lower end elevational view of the same.

Fig. 10 is a perspective view of the complete safe.

Referring now in detail to the drawings, the numeral 1 represents the outer door of the safe, and 2 a pair of horizontal bolts 45 slidably mounted in guides 3 and united by a bridging member 9. Lugs 4 project from the member 9 as shown and are provided with extended pins 5 at the ends. Wheels 6 are rotatably mounted upon shafts 7 in the 50 door 1, and each wheel is provided with a radially extending slotted lug 8.

The member 9 is provided with a relatively wide extension 10 near the middle thereof, a slot 11 being cut in said extension. A plate 12 having one side extending 55 at right angles to the door, at 12^a, is attached

to said extension 10, said side having a recess 13 therein through which projects a stem 17 rigid upon a shaft 16 rotatably mounted in the door 1. Adjacent the plate 12 a second plate 14 is attached, having one side 15 extending out at right angles to said door.

Near the edge of the door 1 is mounted a plate 19 parallel with the member 9, having a circular recess near its upper end through which projects a pin 18 having an extending lug 37 rigid therewith. A slot 38 in said plate 19 communicates with said circular recess, and is of a length substantially equal to that of the lug 37. The pin 18 projects beyond the plate 19, and a link 22 is pivotally attached to the end of said pin, said link being also pivotally supported at about its center at 23. Another link 26 passes through a slot provided therefor in the plate 19, said link 26 being pivoted to the end of the link 22 at 24. Still another link 27 is pivotally attached at about its center at 28, one end being pivoted to the link 26. A projection 29 extends at right angles to the link 27 and passes through a slot provided therefor in the plate 19, terminating in a cap or boss 30. A common type of electric push button 31 is supported rigidly beneath said cap, and wires 32 lead therefrom in the usual manner to an electric source and an electric alarm, not shown. A coiled spring 21 surrounds the pin 18 between the plate 19 and the link 22, and a similar spring 20 surrounds said pin between the door 1 and the plate 19. Said springs normally urge the lug 37 away from the door 1. A button 33 is secured to the stem 18 on the outer side of the door 1, and a button 34 is similarly secured to the shaft 16. Likewise buttons 35 and 36 are secured to the shafts 7. About each of the handles 35 and 36 a graduated circle is described, as shown, on the door 1, so that the positions of the movable parts of the lock mechanism may be identified by the position of a point on the handle relative to said circle. This point on the handle, not shown, may be an arrow or other well-known indicator.

Normally, when the door is locked, the bolts 2 cannot be withdrawn in order to release the door, for they are held by the wheels 6 contacting with the pins 5. Therefore, the first step in opening the door is the 110 turning of the wheels 6 until the slotted lugs 8 will come into alignment with the pins

5, as shown in Fig. 3. Therefore the bolts 2 may be withdrawn so far as the obstruction of the pins 5 is concerned. However, such withdrawal is still prevented, for the raised 5 side 15 of the plate 14 cannot move toward the left because of the obstruction of the plate 25 which is rigid with the link 22, as is apparent in Fig. 1. Therefore, the next 10 step in the opening consists in turning the button 33 until the lug 37 attains a position just over the slot 38, and then said button is pulled outward from said door, thereby drawing said lug through said plate 19 to the other side of said plate, as seen in Fig. 2. 15 This operation causes, as is readily apparent, the cap 30 to press against the button 31, sounding the electric alarm. Likewise this operation causes the plate 25 to be lifted by the link 22 so that it will allow movement to 20 the left of the plate 14. At this stage the button 34 is turned in a counter clockwise direction, causing the bolts 2 to be withdrawn by virtue of the contact of the stem 17 with the lotted extension 13 of the plate 12. 25 Then the door 1 may be swung open.

Additional safety means are provided on the inner-door 40 of the safe. Bolts 41 are united by a bridging member 41^a, in the same manner as the bolts 2. A single wheel 30 42 is rotatably mounted in the door 40, a slot 43 being provided in the periphery of said wheel. A pin 44 rigid with an extension 48 is adapted to align with said slot to allow movement to the left of the member 35 41^a and hence of the bolts 41. A shaft 45

is rotatably mounted in the door 40 and has rigid therewith a stem 46 engaging the raised side 51 of a plate 52 attached to said member by means of a recess in said side. A horizontal slot 49 in the member 41^a allows movement to the left of the said member past the shaft 45. A button 50 on the outside of the door 40 provides means for turning the shaft upon which the wheel 42 is mounted, and a similar button 54 is attached to the shaft 45. 40 45 The operation of this door is the same as described.

I claim:

In a device of the class described, a door, bolts slidably mounted on said door, wheels 50 rotatably mounted adjacent said bolts, slotted radial projections on said wheels, a member connecting said bolts, lugs projecting from said member, pins on the ends of said lugs lying within the peripheries of said 55 wheels, said pins being adapted to register with said slotted lugs, an extension on said member, a slot in said extension, a shaft extending through said slot and rotatably mounted in said door, a stem rigid with said 60 shaft, a projection on said extension, having a recess therein, said stem having contact with said projection through said recess, a second projection on said extension, means normally lying in the path of said second 65 plate, and means for removing said first-named means from the said path.

In witness whereof I affix my signature.

MACIEJ SZYMKIEWICZ.
